UNITED STATES PATENT OFFICE

FREDERICK L. KAHN, OF CHICAGO, ILLINOIS, ASSIGNOR, BY MESNE ASSIGNMENTS, TO ASSOCIATED ELECTRIC LABORATORIES, INC., OF CHICAGO, ILLINOIS, A CORPORATION OF DELAWARE

AUTOMATIC TELEPHONE SYSTEM

Application filed February 12, 1932. Serial No. 592,451.

The present invention relates in general to automatic telephone systems, and its object, broadly stated, is to provide a new and improved switching arrangement for a system employing large capacity connectors. More specifically, the object is to provide a switching arrangement for a system having a capacity of 10,000 lines, wherein only half as many groups of second selectors and connec-

10 tors are required to perform the same switching operations of the well-known automatic telephone systems of 10,000-line capacity.

It is customary in regular 10,000-line systems to provide a large group of first selectors, ten groups of second selectors, and one hundred groups of connectors. However, in some 10,000-line systems the number of groups of connectors have been cut in half by employing large capacity (200-line) connectors, similar to the large capacity connector disclosed in the Tharp application, serial No. 510,680, filed January 23, 1931, instead of the regular (100-line) connectors. In the present system, a large group of first selectors and five groups of second selectors are provided. The reduction in the number of groups of second selectors is accomplished by arranging the trunking between the first and second selectors so that each group of second selec-

20 tors is accessible from two different levels of the first selector. The level over which the second selector is seized determines the test wiper to be used in selecting a 200-line connector. Since only five groups of second selec-

30 tors are required, and each group has ten levels, one for each group of connectors, only fifty groups of 200-line connectors are required. The test wiper used by the second selector in seizing a connector determines the

40 set of wipers to be used by the connector to complete a connection.

There are a number of features, not specifically mentioned at this time, relating to various circuit refinements which will be further discussed in connection with the detailed description of the operation of the apparatus shown in the drawings.

The accompanying drawings, comprising Figs. 1 and 2, show by means of the usual circuit diagrams a sufficient amount of equip-

ment in a telephone system embodying the invention to permit the same to be readily described and understood.

Fig. 1 shows a circuit diagram of a substation A, a lineswitch and master switch represented by the rectangles LS and MS, respectively, a first selector S1, and a second selector S2, both of which are of the Strowger type.

Fig. 2 shows a circuit diagram of a connector H of the Strowger type, and substations B and C.

Referring now to Fig. 1, the substation A is an ordinary automatic telephone substation having the usual talking instrumentalities and a calling device for controlling the automatic switches. The line conductors terminate at the exchange in the individual line-switch LS (represented by the rectangle), which is one of a plurality of lineswitches controlled by a master switch MS (which is also represented by a rectangle). These switches are similar to those disclosed in Patent No. 1,809,086, granted to Voss and Willis June 9, 1931. The first selector S1 is mechanically of the usual well-known Strowger vertical and rotary type. The second selector S2 is mechanically of the well-known Strowger vertical and rotary type except that it has two test wipers and two complete sets of associated bank contacts instead of the usual single test wiper and associated bank contacts. Besides the usual relays and magnets, this switch has an additional switching relay which allows the normally-connected test wiper to be used, or switches to the test wiper normally disconnected, depending upon which level of the first selector the call comes in over.

Referring now to Fig. 2, the connector H is mechanically of the usual and well-known Strowger vertical and rotary type, except that it has two sets of wipers and a corresponding number of associated sets of banks. Besides the usual relays and magnets, this switch has an additional switching relay which allows the normally-connected set of wipers to be used, or switches to the normally-disconnected set of wipers, depending upon the test wiper used by the second selector in

seizing the connector. The banks are divided into two units, one for each set of wipers, and each unit has lines extending to subscribers' stations in a different hundreds group.

5 A subscriber's line is shown extending from the bank contacts accessible to the normally-connected set of wipers, to substation B, which is similar to substation A, and to the subscriber's individual lineswitch (not shown), which is similar to lineswitch LS.

10 Another subscriber's line is shown extending from the bank contacts accessible to the normally-disconnected set of wipers, substation C, which is similar to substations A and B, 15 and to the subscriber's individual lineswitch (not shown), which is similar to lineswitch LS.

20 The present system, having been described in general, will now be described in connection with a detailed description of the operation of the apparatus shown on the drawings. For this purpose it will be assumed that the subscriber at substation A, Fig. 1, desires to 25 converse with the subscriber at substation B, Fig. 2.

When the receiver is removed at substation A, a circuit is closed across line conductors 11 and 12, and the subscriber's individual lineswitch LS is operated in the well-known 30 manner and seizes an idle trunk line extending to a first selector. It will be assumed that the first selector S1 is seized by the lineswitch LS, over trunk conductors 133-135. Responsive to the seizure of the first selector 35 S1, the line relay 101 is energized over the following circuit: from battery, upper winding of line relay 101, armature 121 and its resting contact, conductor 133, contact springs 21 and lineswitch LS, line conductor 11, subscriber's loop, line conductor 12, lineswitch LS and contact springs 24, conductor 135, armature 125 and its resting contact, lower winding of relay 101, normally closed contacts of overflow springs 130, one side of 45 dial tone transformer 132, to ground.

When the line relay 101 operates, it opens a point in the circuit of vertical magnet 105 at armature 109 and its resting contact, and at armature 108 and its front contact it closes 50 a circuit for the upper winding of release relay 102 in series with the lower windings of series relay 103 and release relay 102. More in detail, the circuit closed at armature 108 and its front contact is as follows: from 55 ground, normally-closed contacts 116 of the vertical off-normal springs VON, normally-closed contacts controlled by armature 112, upper winding of release relay 102, armature 108 and its front contact, lower winding of 60 series relay 103, lower winding of release relay 102, to battery. The current flow through this circuit is sufficient to operate release relay 102, whose upper winding has a 65 relatively large number of turns, but series relay 103 is not operated in this circuit be-

cause the lower winding of relay 103 has only a relatively small number of turns. The same is true as regards the lower winding of relay 102.

70 When relay 102 operates, it opens a point in the circuit of release magnet 107 at armature 110 and its resting contact; places a ground potential on release trunk conductor 134 at armature 113 and its front contact to maintain the lineswitch LS in its operated position, and also to maintain a ground potential on conductor 13 to maintain the subscriber's line busy to all connectors having access thereto; disconnects the ground potential for its upper winding at the normally-closed contacts controlled by armature 112, and by 75 the same action substitutes a ground potential directly to the upper winding at armature 112 and its front contact; and at armature 111 and its front contact it applies 80 ground potential by way of contacts 116 of vertical off-normal springs VON, to the upper winding of series relay 103. This completes a circuit through the upper winding 85 of relay 103 in series with the lower winding of relay 102, in which circuit the upper winding of relay 103 is shunted around the upper winding of relay 102 and the lower winding of relay 103. The closing of this new 90 circuit does not disturb the previously-operated relay 102, but it results in the strong magnetization of and the immediate operation of series relay 103, as the upper winding of relay 103 comprises a relatively large number of turns.

95 When relay 103 operates, it prepares a new circuit for its own upper winding at armature 117 and its front contact; opens a point in the circuit for the rotary magnet 106 at armature 118 and its resting contact; and at armature 115 and its front contact it prepares 100 a circuit for the vertical magnet 105.

105 It should be noted that the original energizing circuit for relay 102 includes ground at the normally-closed contacts 116 of the vertical off-normal springs VON. It sometimes happens that a selector becomes stuck mechanically and does not restore; consequently the vertical off-normal springs remain in an operated position. Due to the 110 way in which the master switch MS tests the bank contacts to which the release conductors, similar to release conductor 136, are connected, it will stop on a trunk line leading to a selector that is not in normal position, if there is an absence of ground potential on the release conductor thereof. With the selector in an off-normal position 115 it will be seized by a lineswitch such as lineswitch LS. However, when this happens, the release relay 102 does not operate, owing to the fact that the circuit is not completed at the vertical off-normal springs 116, and the lineswitch LS releases due to the fact that the holding ground potential is not applied to 120 125 130 135

conductor 134 by armature 113 of relay 102. When the lineswitch releases, the plunger will align itself with the shaft controlled by the master switch, due to the fact that it is 5 a self-aligning lineswitch, and will plunge again to seize a newly-selected idle trunk to another selector.

From the foregoing explanation, it is seen that, responsive to the operation of the line 10 relay 101 when the selector relays 102 and 103 operate successively, and that the selector is thereby prepared for operation in response to the usual manipulation 15 of the calling device by the subscriber at sub-
station A.

Since the circuit of the lower winding of line relay 101 includes the secondary winding of the dial tone transformer 132, dial tone current is transmitted over conductor 20 135 to the calling subscriber at substation A, and back over conductor 133 and the upper winding of relay 101 to battery, thereby giving a characteristic signal to the calling subscriber to inform him that he may now start 25 to dial the desired number.

When the first digit of the desired number is dialed, line relay 101 is deenergized momentarily a number of times, depending upon the value of the dialled digit. Each time it 30 is momentarily deenergized, line relay 101 closes a circuit for the vertical magnet 105 at armature 109 and its resting contact, whereupon the vertical magnet 105 is operated to raise the shaft of the switch, together 35 with the wipers affixed thereto one step. By the operation of the vertical magnet, the wipers are, therefore, raised step by step until they come to rest opposite the desired level of bank contacts. As a further result 40 of each momentary deenergization of the line relay 101, the initial circuit for the upper winding of relay 102 through the lower windings of relays 103 and 102 is opened at armature 108 and its front contact, and at 45 the normally-closed contact controlled by armature 108 a short circuit is placed around the upper winding of release relay 102. In addition, a circuit is completed for the upper winding of relay 103 in series with the 50 lower winding of relay 102 at the normally-closed contact controlled by armature 108, armature 117 and its front contact, contacts 55 137 of the vertical off-normal springs VON (closed on the first vertical step of the switch), armature 111 and its front contact, upper winding of relay 103, lower winding 60 of relay 102, to battery. Series relay 103 is maintained in its energized position over this circuit. Since the lower winding of relay 102 has only a relatively small number of turns, it cannot remain operated in series 65 with the upper winding of relay 103. How-

ever, together with the shunt around the upper winding and the current flow through the lower winding, release relay 102 is held operated between successive impulses.

Each time line relay 101 reoperates following the delivery of an impulse to the vertical magnet 105, it removes the shunt from around the upper winding of relay 102 at the normally-closed contact controlled by armature 108, whereupon the upper winding of relay 102 is again included in a circuit in series with the lower windings of relays 103 and 102 by the closing of armature 108 and its front contact. In addition, a circuit is now completed for the upper and lower windings of release relay 102 in series with the upper winding of series relay 103 due to the fact that contacts 137 of the vertical off-normal springs VON have been closed on the first vertical step of the switch, over the following circuit: from ground, armature 112 and its front contact, upper winding of relay 102, armature 117 and its front contact, contacts 137 of the vertical off-normal springs VON, armature 111 and its front contact, upper winding of relay 103, lower winding of relay 102, to battery. It should be noted that a circuit is closed for both windings of release relay 102 over two separate paths, one path including the lower winding of series relay 103, and the other path including the upper winding of series relay 103. Relay 102 is fully energized again over this circuit, while the current flowing through the windings of relay 103 in series with the windings of relay 102 is insufficient to maintain relay 103 operated, but relay 103 remains operated during the receipt of the remaining impulses due to the fact that the current flowing through both its windings makes the relay 105 slow to release.

By way of an explanation, the first time line relay 101 energizes, release relay 102 also energizes and causes series relay 103 to energize. The first deenergization of line relay 101, during impulsing, causes the vertical magnet to step the wipers up one step, opening contacts 116 and closing contacts 137 of the vertical off-normal springs VON. Line relay 101 also places a shunt around the high resistance upper winding of release relay 102, and by the same action it completes a circuit for the high resistance upper winding of series relay 103 in series with the low resistance lower winding of release relay 102. The shunt around the upper winding and the current flow in the lower winding of relay 102 is just sufficient to keep the relay energized until the line relay is again operated, during impulsing, to again complete the energizing circuit for the release relay 102. When the line relay 101 energizes again, after the first deenergization, the high and low resistance windings of release relay 102 are included in the circuit of the lower winding of series relay 120 125 128

103 over one path, and the upper winding of series relay 103 in the other path. The amount of current flowing in this circuit is sufficient to keep the release relay 102 energized, but the current flowing through both windings of series relay 103 is only sufficient to maintain the relay 103 energized during impulsing.

When line relay 101 comes to rest in an energized condition at the termination of the series of impulses, the series relay 103 subsequently restores to normal, due to the fact that the current flow in both windings of the relay is insufficient to maintain the relay energized, but is sufficient to make the relay slow to release. Upon restoring, relay 103 disconnects its own upper winding at armature 117 and its front contacts, to prevent the relay from operating until the selector 15 has been released and again seized. The opening of this circuit also opens the path of the energizing circuit of release relay 102, which includes the upper winding of relay 103. However, release relay 102 remains energized 20 over the other path which includes the lower winding of series relay 103. As a further result of the falling back of series relay 103, the circuit to the vertical magnet 105 is opened at armature 115 and its front contact, and at 25 armature 118 and its resting contact it closes a circuit for the self-interrupting rotary magnet 106.

For the purpose of this description it will be assumed that the digit received at the first selector is the digit 1, in which case the wipers 127-129 have been raised one step and are now standing opposite the first level of the bank contacts.

Therefore, when the series relay 103 falls 40 back and closes armature 118 and its resting contact, the self-interrupting circuit for the rotary magnet 106 is completed as follows: from ground, armature 113 and its front contact, contacts 119 of the vertical off-normal springs VON (closed on the first vertical step), armature 114 and its front contact, armature 118 and its resting contact, contacts 120 of the overflow springs OF, armature 124 and its resting contact, self-interrupting contacts and windings of the rotary magnet 106, to battery.

The automatic rotation of the wipers 127-129, responsive to the buzzer-like action of the rotary magnet 106, continues until an 55 idle trunk is encountered. When an idle line is encountered (for example, the line comprising conductors 138, 140, and 141 extending from the first-level bank contact set to the second selector S2), a battery potential 60 is encountered by test wiper 128 by way of test conductor 140 and the lower winding of relay 234, completing an operating circuit for the upper winding of switching relay 104 to ground at armature 113 and its front contact. Upon energizing, relay 104 opens

the circuit of the rotary magnet 106 at armature 124 and its resting contact (thereby terminating the rotary movement), and at the same time completing a locking circuit for its lower winding in series with the rotary magnet 106 at armature 124 and its front contacts. Rotary magnet 106 does not operate in series with the lower winding of relay 104 on account of the high resistance of this winding. Relay 104 also opens a point 70 in the circuit for release magnet 107 at armature 122 and its resting contact; extends the ground potential on test conductor 134 through to test wiper 128 at armature 123 and its front contact, thereby short circuiting its upper winding; and at armatures 121 and 125 of their respective resting contacts disconnects the incoming conductors 133 and 135 from the windings of the line relay 101 and extends them by way of the front contacts of armatures 121 and 125, wipers 127 and 129, conductors 138 and 141, armatures 221 and 225 and their respective resting contacts, to the windings of line relay 201 of the second selector S2.

In case selector S1 fails to find an idle trunk line leading to a second selector and continues to rotate until the wipers 127-129 pass beyond the last set of contacts, the contacts 120 and 130 of the overflow spring combinations OF are actuated. Contacts 120 of the overflow spring OF open the self-interrupting circuit to the rotary magnet 106, thereby terminating the rotary movement, while at contacts 130 of the overflow springs OF busy tone current is substituted for dial tone current, giving the calling subscriber a characteristic busy signal. The calling subscriber upon hearing the busy signal replaces his receiver, thereby releasing the partially-established connection.

It has previously been stated that the switching relay 104 energized and switched the connection through to the second selector S2, when the test wiper 128 encountered a battery potential. When the test conductor 128 encountered the bank contact terminating conductor 140, battery was encountered by the test wiper 128 over the following 115 circuit: conductor 140, lower winding of relay 234, contacts 232 of the vertical off-normal springs VON, resistance 231, to battery. Switching relay 104, of the first selector S1, and relay 234, of the second selector S2, both energize over this circuit. The operation of relay 104 has been described in detail hereinbefore. Relay 234, upon operating, prepares a locking circuit for its upper winding at armature 236 and the front contacts, and at armature 235 and its front contact it connects up the normally disconnected test wiper 229.

It might be well to mention at this time that if the first selector S1 had been operated to the second level, the second selector S2 may

be seized as before inasmuch as the line conductors are multiplied between bank contacts of the first and second levels. It should be noted, however, that the test wiper 128 of 5 the first selector will encounter the battery potential over conductor 139 of the selector S2. When this occurs, the relay 234 is not energized in series with the switch-through relay 104 of selector S1. Therefore, the normally connected test wiper of the second selector S2 will be used in completing a connection to the connector.

When the second selector S2 is seized by the first selector S1, over conductors 138 and 141, line relay 201 energizes over the previously-traced circuit. Responsive to the energization of the line relay 201, release relay 202 and series relay 203 successively energize. The line relay 201, release relay 202, series 20 relay 203, and switching relay 204 of the second selector S2, are operated in the same manner as has been previously described in connection with line relay 101, release relay 102, series relay 103, and switching relay 104 25 of the first selector S1.

At armature 213 and its front contact, release relay 202 completes a locking circuit for relay 234 by way of armature 236 and its front contact, and by way of the lower winding of relay 234 and conductor 140 places a ground on release trunk conductor 140 to maintain the switching relay 104 of the selector S1 energized after the subsequent release of the line relay 101 and release relay 30 35 102. The switching relay 104 is maintained energized over the following circuit: grounded test conductor 140, test wiper 128, armature 123 and its front contact, lower winding of relay 104, armature 124 and its front contact, self-interrupting contacts and winding of the rotary magnet 106, to battery.

When the second digit of the desired number is dialled by the calling subscriber, line relay 201 of the second selector S2 is de- 45 energized momentarily a number of times depending on the value of the digit dialled. Each time it is momentarily deenergized, line relay 201 closes a circuit for the vertical magnet 205, whereupon the vertical magnet 205 50 is operated to raise the shaft of the switch, together with wipers 227-230, one step. The wipers, therefore, are raised step-by-step until they come to rest on the desired level of bank contacts. When the line relay 201 55 comes to rest in an energized condition at the end of the second series of impulses, the slow-to-release series relay 203 thereupon falls back. Among other things, the series relay prepares the self-interrupting circuit for the 60 rotary magnet 206 at armature 218 and its resting contact.

For the purpose of this description, it will be assumed that the digit received at the second selector S2 is the digit 1, in which case 65 the wipers 227-230, inclusive, have been

raised one step and are now standing opposite the first level of bank contacts. When the series relay 203 falls back and completes the self-interrupting circuit for the rotary magnet 207 at armature 218 and its resting contact, the rotary magnet 207 rotates the wipers over the first level of the bank contacts. The circuit for operating the rotary magnet 207 is as follows: ground at armature 213 and its front contact, contacts 219 of the vertical off-normal springs VON (closed on the first vertical step of the switch), contacts 220 of the overflow springs OF, armature 214 and its front contact, armature 218 and its resting contact, armature 224 and its resting contact, self-interrupting contact and winding of the rotary magnet 206, to battery. 70 75 80 85 90

The automatic rotation of the wipers, responsive to the buzzer-like action of the rotary magnet 207, continues until switching relay 204 operates upon an idle trunk encountered by the test wiper 229. Since the test wiper 228 has been disconnected at armature 225 and its resting contact, the test wiper 95 99 103 107 111 115 119 123 127 131 135 139 143 147 151 155 159 163 167 171 175 179 183 187 191 195 199 203 207 211 215 219 223 227 231 235 239 243 247 251 255 259 263 267 271 275 279 283 287 291 295 299 303 307 311 315 319 323 327 331 335 339 343 347 351 355 359 363 367 371 375 379 383 387 391 395 399 403 407 411 415 419 423 427 431 435 439 443 447 451 455 459 463 467 471 475 479 483 487 491 495 499 503 507 511 515 519 523 527 531 535 539 543 547 551 555 559 563 567 571 575 579 583 587 591 closed contacts of armatures 312 and 313 to the upper and lower windings of line relay 302 to battery and ground, respectively, of the connector H. Line relay 302 energizes 5 over this circuit.

Responsive to the above-mentioned operation of line relay 302, the release relay 303 of the connector H operates. At armature 320 and its front contact, the release relay 10 303 returns ground by way of conductor 240, to provide a holding circuit for the preceding apparatus after the slow-acting release relay 202 of the selector S2 has fallen back, as will now be explained.

15 When the line relay 201 is disconnected at the resting contacts of armatures 221 and 225, respectively, it opens the circuit including the upper and lower windings of release relay 202 at armature 208 and its front contact, and it places a shunt around the upper winding of relay 202 at the resting contacts controlled by armature 208. The releasing of the line relay does not close a circuit to the vertical magnet 205, due to the fact that 20 the series relay 203 is in its normal deenergized position. Due to the fact that the release relay 202 is made somewhat slow to release, ground is returned by way of armature 320 of release relay 303, to hold the selector S2 and preceding switches operated. The circuit for holding the switching relay 204 and relay 234 of the selector S2 and the preceding switches operated is as follows: 25 ground at armature 320 and its front contact, conductor 240, test wiper 229, armature 235 and its front contact, armature 223 and its front contact; one branch of the circuit including the lower winding of switching relay 204, armature 224, self-interrupting springs 30 and winding of the rotary magnet 206, to battery; the other branch including armature 236 and its front contact, upper winding of relay 234 and battery; the third branch extending ground over test conductor 140 of 35 the selector S2 to the preceding switches.

40 It has been mentioned before that the line relay 302 and the release relay 303 of the connector energize when the switch is seized. When the line relay 302 is operated over conductors 238 and 241, the normal shunt around the upper winding of release relay 303 is removed, and an energizing circuit is completed for the relay 303 over the following circuit: ground, upper winding of 45 release relay 303, armature 317 and its front contact, lower winding of series relay 304, lower winding of release relay 303, to battery. Release relay 303 energizes over this circuit, and at armature 322 and its front contact 50 closes a circuit for the upper winding of series relay 304 in series with both of the windings of release relay 303. However, due to the fact that the high resistance upper winding of release relay 303 is included in the 55 circuit for the upper winding of series relay

304 over one path and in series with the lower winding of relay 304 over the other path, the series relay 304 does not energize. In addition, ground potential is connected to conductor 240 at armature 320 and its front contact to hold the preceding switches in their operated position, as has been described. Release relay 303 also opens a point in the circuit for the release magnet 309 at armature 319 and its resting contact, prepares an impulsive circuit for the vertical and rotary magnets at armature 323 and its front contact, and at armature 321 and its front contact it completes an energizing circuit for the combination ring-cut-off and switch-over 60 relay 305 over the following circuit: ground, armature 321 and its front contact, contacts 327 of the vertical off-normal springs VON, lower winding of relay 305, to battery. Relay 305 energizes over this circuit and prepares a circuit for the vertical magnet at armature 330 and its front contact.

65 The calling subscriber may now manipulate his calling device in accordance with the third digit in the telephone number of the wanted subscriber. When the third digit of the desired number is dialled, relay 302 is de-energized momentarily a number of times depending on the value of the digit dialled. Each time it is momentarily deenergized, line relay 302 closes a circuit for the vertical magnet 310 at armature 318 and its resting contact, whereupon vertical magnet 310 is operated to raise the shaft of the switch, together with the wipers 356-361, inclusive, one step. By the operation of the vertical magnet, the wipers are, therefore, raised step-by-step until they come to rest opposite the desired level of bank contacts. As a further result of each momentary deenergization of the line relay 302, the upper winding of release relay 303 is shunted by the ground at the normally closed contacts controlled by armature 317, and an operating circuit is completed for the upper winding of relay 304 in series with the lower winding of relay 303. In addition, the circuit through the lower winding of relay 304 and lower winding of relay 303 is opened at armature 317 and its front contact. The current flow through the upper winding of relay 304 is sufficient to cause the relay to energize while the current flow through the lower winding of release relay 303 is insufficient to maintain relay 303 in its energized position. However, together with the shunt around the upper winding of the relay, it is made slow to release. Therefore, the release relay 303 remains energized throughout the series of 100 impulses.

105 Each time line relay 302 reoperates following the delivery of an impulse to the vertical magnet 310, it removes the shunt around the upper winding of release relay 303 and again establishes the initial energizing circuit for 110

the release relay at armature 317 and its front contact, which includes both of the windings of the release relay in series with the lower winding of the series relay 304. The current 5 flow through both of the windings of relay 304, each of them in a separate series circuit with the upper and lower windings of relay 303, is not sufficient to maintain the relay 304 in its energized position. However, the relay 10 is made slow to release. Therefore, the series relay 304 will remain in its energized position throughout the series of impulses.

The first momentary deenergization of the line relay 302 completes a circuit for the vertical magnet 310, and the series relay 304 is 15 operated in the manner previously described. At armature 326 and its front contact relay 304 completes a locking circuit for relay 305. As soon as the vertical magnet raises the 20 wipers of the switch one step, contacts 351 of the vertical off-normal springs VON open and remove the battery potential from the test conductor 240; contacts 327 of the vertical off-normal springs VON open a point in the 25 initial energizing circuit for the relay 305; and contacts 324 of the vertical off-normal springs VON prepare a circuit for the release magnet 309.

It will be assumed that the vertical magnet 310 has raised the wipers 356—361, inclusive, opposite the bank contacts shown on the drawings, responsive to the first digit received at the connector H. When the line relay 302 comes to rest in its operated condition, 30 the current flow through the series relay 304 is not sufficient to maintain the relay in its energized position, but it does retard the releasing action of the relay. Relay 304 subsequently releases, and at armature 326 and 35 its front contact it opens the locking circuit for relay 305. Relay 305 releases and opens the impulsive circuit for the vertical magnet 310 at armature 330 and its front contact, while at armature 330 and its resting contact 40 it prepares the impulsive circuit for the rotary magnet 311.

The calling subscriber may now transmit the final digit of the wanted subscriber's number. The line relay is momentarily deenergized a number of times, thereby causing the series relay 304 to operate in series with the release relay 303 in the manner previously described. In addition, each time the line relay falls back momentarily, it completes a 45 circuit for the rotary magnet 311 as follows: ground, armature 318 and its resting contact, armature 323 and its front contact, armature 326 and its resting contact, armature 345 and its resting contact, armature 330 and its resting 50 contact, winding of rotary magnet 311, to battery. By the operation of the rotary magnet 311, the wipers 356—361, inclusive, are rotated step by step and are finally brought to rest in engagement with the set of bank contacts of the line of sub-station B. It should

be noted that the wipers 359—361, inclusive, have also engaged the bank contacts of the line of substation C. However, due to the fact that the wiper switching relay 308 has not been operated, the engagement of the associated bank contacts by these wipers does not have any effect at this time. 70

It will be assumed that the called line is busy, when the wipers of the connector engage the bank contacts of the called line. Therefore, the two-step busy-test relay 306 will be energized in its first step over the following circuit: ground by way of test conductor 363, test wiper 357, armature 354 and its resting contact, normally-closed contacts controlled 75 by armatures 340 and 333, armature 325 and its front contact (relay 304 being slow to release does not fall back immediately after the last impulse has been transmitted to the rotary magnet), armature 341 and its resting contact, resistance element 335, two-step busy-test relay 306, to battery. Relay 306 energizes in its first step only and prepares a circuit at armature 334 and its front contact A, 80 for energizing itself in its second step. Relay 304 subsequently releases and transfers the ground potential by way of the normally-closed contacts controlled by armature 325, armature 334 and its front contact A, winding of the busy-test-relay 306, to battery. The 85 resistance element 335 is disconnected from the circuit for relay 306, permitting sufficient current to flow through the winding of the relay to allow it to energize in its second step to operate all its armatures. When the busy-test relay 306 is operated to its second step, it 90 completes a locking circuit for itself by way of armature 333 and its front contact and the grounded conductor 240; at the same time, it opens its initial energizing circuit by way of test wiper 357 and the grounded test conductor 363; it opens the circuit for the rotary magnet at armature 336 and its resting contact; at armature 332 and its front contact it connects the busy-tone conductor to one side 95 of the line. The busy-signalling current is transmitted back over the established connection to the calling subscriber. The subscriber upon hearing the busy signal, will replace his receiver, whereupon the established connection is released in the manner to be explained hereinafter. 100

In the present case, however, it will be assumed that the line of substation B is idle 105 when the wipers 356—358, inclusive, come to rest on the terminals of the called line, in which case the busy relay 306 is not energized. Therefore, shortly after the termination of the rotary movement the slow-to-release series relay 304 subsequently falls 110 back and completes the circuit for the slow-acting switching relay 307, as follows: grounded test conductor 240, armature 353 and its resting contact, upper winding of switching relay 307, armature 334 and its 115 120 125 130

resting contact, normally closed contacts of armature 325, normally closed contacts controlled by armatures 333 and 340, respectively, armature 354 and its resting contact, test 5 wiper 357, thence to battery by way of the bridge-cut-off winding of the associated line-switch (not shown), which lineswitch may be the same as the lineswitch LS, associated with the line of substation A. Responsive 10 to the closure of this circuit, the bridge cut-off of the lineswitch is operated to disconnect the line relay of the lineswitch from across the line conductors.

In the connector H, switching relay 307 energizes over the above-traced circuit, and at 15 its lightly-adjusted armature 342 completes a locking circuit for its lower winding from ground at armature 321 and its front contact; places a direct ground on test wiper 357 20 at armature 340 and its front contact; opens the point in the circuit for the rotary magnet at armature 345 and its resting contact; and at armatures 338 and 350 and their respective front contacts connects up the line wipers 356 and 358, whereupon ringing current 25 is projected over the called line to ring the bridged ringer at the substation B. At armature 337 and its front contact, switching relay 307 connects the ring-back-tone conductor to the calling line, to indicate to the calling subscriber that the wanted subscriber's line is being signalled. The return path 30 for the ringing current includes the line wipers 356 and the upper winding of the combination switch-over and ring-cut-off relay 305 35 and ground.

When the called subscriber at substation B responds to the ringing of his bell by removing his receiver, a direct current bridge is 40 closed across the associated line conductors, whereupon ring-cut-off relay 305 energizes. Upon energizing, the ring-cut-off relay 305 45 closes a locking circuit for itself at its lightly-adjusted armature 329; disconnects the line wipers 356 and 358 from its own upper winding and the generator lead at armatures 328 and 331, respectively; opens the ring-back-tone circuit for the calling subscriber at the normally closed contacts controlled 50 by armature 328; and it completes the talking connection at armatures 328 and 331 and their respective front contacts.

Current is now supplied to the transmitter at substation B through the windings of 55 the double-wound back-bridge relay 301, which is accordingly energized. This relay is a reversing relay and has the well-known function of reversing the incoming trunk conductors 238 and 241, as regards their connections with the winding of line relay 302. Relay 301 opens a point in the circuit for the release magnet 309 at armature 350 and its resting contact, and at armature 314 and its front contact it closes an additional holding 60 circuit for the lower winding of switching

relay 307. The reversing of the line conductors 238 and 241 is a standard operation, and is for the purpose of operating a subscriber's paystation or metering apparatus, and in some cases is used for supervisory purposes. The desired connection is now completed and the subscriber may converse as desired. 70

When the conversation is completed, both subscribers replace their receivers. Should the calling subscriber restore his receiver first, the line relay 302 of the connector H will deenergize and open the circuit of the slow-to-release relay 303. Relay 303 subsequently deenergizes and removes the ground from test conductor 240 at armature 320 and its front contact, releasing the succeeding switches in the usual manner. The connector H does not release due to the fact that the circuit for the release magnet 309 80 is opened at armature 315 and its resting contact. The connector cannot be seized by any selector, such as selector S2, because the battery potential is disconnected from the test conductor 240 at armature 339 and its resting contact. Armature 339 is held in its operated position by relay 307, which in turn is locked up from ground at armature 314 and its front contact. When the called subscriber hangs up his receiver, relay 301 deenergizes, opening the locking circuit for switching relay 307 and completing the circuit for the release magnet 309. Relay 307, upon falling back, opens the circuit for relay 305, which also falls back. When the release magnet 309 is operated, the switch 90 restores to normal in the usual manner. The battery potential is again applied to conductor 240 as soon as the contacts 351 of the vertical off-normal springs VON are closed when the switch is restored to its normal position. 95

If the called subscriber at substation A hangs up first, the connector H is then released under control of the calling subscriber. It might be well to point out that when the ground is removed from the release trunk conductor 240 to restore the preceding switches, the switch-through relay 204 and the relay 234 of the selector S2 restore to normal. When the switch-through relay 204 releases, a circuit is completed for the release magnet 207, whereupon the switch is restored to normal in the usual manner. The releasing of the first selector S1 of the lineswitch LS is performed in the usual manner. 100

From the foregoing description of the operation of the system, it is evident that the selection of the wiper set in the connector H is automatically controlled over the test wipers in the second selector S2, which in turn are controlled over the test conductor of the level selected by the first selector S1. Particular attention should be paid to the arrangement whereby relay 234 of the sec- 110 120 130 135

ond selector S2 is operated over the test conductor 140 when the first selector S1 is dialled to the first level and is shunted out when the first selector S1 is operated to the 5 second level. Relay 234 determines which of the two test wipers in the second selector S2 is to be used in searching for a connector. The connector H is provided with two wiper sets, one of which is connected up 10 when relay 308 is operated over test conductor 239 and the other of which is used when the relay 308 is shunted out by the extension of a connection over test conductor 240.

It will now be assumed that a subscriber at 15 substation A desires to establish a connection with the subscriber at substation C. For the purpose of description, it will be assumed that lineswitch LS is operated in the usual manner and seizes the first selector S1, as 20 has been described before. When the subscriber receives the dial-tone, he will dial the first digit of the wanted subscriber's number, which in this case is the digit 2. This will raise the wipers 127-129, inclusive, opposite 25 the second level of bank contacts. It will be assumed that the wipers are then rotated into the bank in the usual manner, and engage the contacts to which the conductors 138, 139, and 141, extending to the second selector S2, are 30 connected. The battery potential required to operate the switch-through relay 104 of the first selector is now encountered over conductor 139, contacts 232 of the vertical off-normal springs VON, resistance element 231, 35 to battery. The switch-through relay 104 operates as before, but in this case through the resistance 231 and battery direct, instead of operating in series with relay 234. Ground is returned to hold the first selector S1 operated 40 as soon as the release relay 202 of the second selector S2 is operated responsive to the energization of the line relay 201.

It will be assumed that the digit dialled to 45 the second selector S2 is the same digit dialled in establishing the previous connection, i. e., the wipers 227-230 has been raised by the operation of the vertical magnet, and are now standing on the level corresponding to the level over which the connector H is accessible. When the selector S2 automatically rotates to select an idle connector, it will be assumed in this case that the connector H is 50 the one selected. The test wiper 229 may encounter battery over the release trunk conductor 240, but inasmuch as the relay 234 has not been operated to connect up the test wiper 229 at armature 235 and its front contact, the battery potential encountered by the test wiper 229 has no effect at this time. However, 55 the test wiper 228, which is the test wiper that is now connected by way of the resting contact of armature 235, encounters a battery potential on test conductor 239. When the battery potential is encountered by test wiper 228, switch-through relay 204 of the selector

S2 and wiper-switching relay 308 of the connector H are energized in series over the following circuit: Battery, resistance element 352 of the connector H, contacts 351 of the vertical off-normal springs VON, armature 339 and its resting contact, upper winding of wiper-switching relay 308, test conductor 239, test wiper 228, armature 235 and its resting contact, upper winding of switching relay 204, armature 213 and its front contact, to ground. When the switch-through relay 204 is operated, the line relay of the connector H is energized responsive to the energization of the line relay 302 and completes a locking circuit at armature 321 for the lower winding of the wiper-switching relay 308. At armature 320 and its front contact, relay 303 grounds the release trunk conductor 239 by way of the upper winding of wiper-switching relay 308 to hold the switching relay 304, 70 of the selector S2, energized in series with the rotary magnet 206, in the regular manner. In addition, ground is returned over conductor 139 to hold the preceding switches 75 operated.

The calling subscriber now dials the last two digits of the wanted subscriber's number, which are the same as the ones required to establish a connection with the subscriber at substation B. The vertical magnet responds to the impulses dialled and raises the wipers 356-361, inclusive, to the level in which the line of subscriber's station C is terminated. Responsive to the last series of impulses, the rotary magnet rotates the wipers into engagement with the bank contact terminating conductors 362-367. Due to the fact that the wiper-switching relay has been operated, the wipers 356-358, inclusive, are disconnected and have no effect at this time. If the wanted subscriber at substation C is 90 busy at this time, the test wiper 260 will encounter ground potential over test conductor 366, thereby causing the busy-test relay 306 to operate in the manner hereinbefore described.

It will be assumed, however, that the subscriber at substation C is not busy when the wipers 359-361 engage the line; therefore, the switch-through relay 307 is energized and locked up over its lower winding. Ringing current is transmitted to signal the subscriber at substation C as before. When the subscriber responds to the ringing of his bell by removing the receiver, the ring-cut-off relay is operated and the talking connection is completed between the subscriber at substation A and the subscriber at substation C in the usual manner.

The release of the connection is substantially the same as has been previously described. The only difference in the release of the connection is that the wiper-switching relay 308 is released at the same time that the switch-through relay 307 is released.

It is evident from the foregoing disclosure and description that the level dialled in the first selector determines the wiper set to be used in the connector to complete a connection, 5 and also that only half as many groups of second selectors are required due to the fact that each second selector group is accessible over two levels. When the second selector is seized over one level, an auxiliary relay is 10 energized to connect up a normally disconnected test wiper of the second selector, while if the second selector is seized over another level, the auxiliary relay is not energized, and, therefore, the normally connected test 15 wiper is used. The test wiper used in the second selector determines which of the two sets of wipers in the connector will be used to complete the connection to the wanted subscriber.

20 What is claimed is:

1. In an automatic telephone system, a switch train responsive to the digits of a called number to extend a connection, said switch train comprising a first switch responsive to a first digit, a second switch responsive to a second digit, and a last switch responsive to the last two digits of said number, a plurality of wiper sets on said last switch, two test wipers and a single set of 25 line wipers in said second switch, means in said second switch dependent upon the level selected by the first digit for selecting one of said test wipers, and means in said last switch dependent upon the test wiper 30 used by the second switch in selecting said last switch for selecting one of said wiper sets.

2. In an automatic telephone system, a plurality of serially related switches used in 40 extending a talking connection, a second switch having a set of line wipers and a normally connected and a normally disconnected test wiper, a first switch, two test conductors each extending from a different level 45 of said first switch to said second switch, means in said second switch for applying a particular potential to said test conductors, means included in the circuit of one of said test conductors for connecting up the normally 50 disconnected test wiper, means in said first switch responsive when said second switch is selected over one of said test conductors for extending the connection from the first to the second switch and for operating the 55 means for connecting up the normally disconnected test wiper in said second switch, a last switch having a plurality of wiper sets, and means in said last switch dependent upon the test wiper used by said second 60 switch in selecting said last switch for determining the wiper set over which said connection is to be completed.

3. In an automatic telephone system, a plurality of serially related switches for extending 65 a connection, a first switch having two

line wipers and a test wiper, a trunk line comprising two line and two test conductors extending from said first switch to a second switch, said second switch having two line wipers and a normally connected and a normally disconnected test wiper, a trunk line comprising two line and two test conductors extending from said second switch to a last switch, said last switch having a plurality of wiper sets, means for positioning the wipers of said first switch to select said second switch over said two line conductors and one of said two test conductors or over said two line conductors and the other of said two test conductors, means in said second switch dependent upon the test conductor selected by said first switch for determining the test wiper to be used by said second switch in selecting said last switch, means for positioning the wipers of said second switch to select 85 said last switch, and means in said last switch dependent upon the test conductor selected by said second switch for determining the wiper set to be used to complete said connection.

4. In an automatic telephone system, a switch accessible to other switches over two levels, separate test conductors extending from said other switches to said switch, a normally connected and a normally disconnected test wiper and two line wipers, means responsive when said switch is selected over one of said test conductors for connecting up the normally disconnected test wiper, said means non-responsive when said switch is seized over the other of said test conductors to permit the normally connected test wiper to be used, said line wipers being used to complete the connection regardless of the test conductor used in selecting the switch.

5. In an automatic telephone system, a switch train comprising three switches, the second switch being accessible to the first switch over two paths, one path comprising two line conductors and a first test conductor, the other path comprising a multiple of said line conductors and a second test conductor, a plurality of wiper sets on the third switch, means for controlling said first switch to select said second switch over either of said paths, and means in said second switch controlled over the test conductor of the path selected by said first switch for determining the wiper set to be used in said third switch.

6. In an automatic telephone system, a plurality of serially related switches used to establish a connection, the first of said switches being accessible over two paths, one of said paths including two line conductors and a first test conductor, the other of said paths including a multiple of said line conductors and a second test conductor, the second of said switches having two wiper sets over which connections are completed and being accessible over a single path including 130

two line conductors and two test conductors, means for seizing said first switch and for operating it into connective relation with said second switch, and means dependent upon the test conductor used in seizing said first switch for determining the test wiper to be used by said first switch on seizing said second switch.

7. In an automatic telephone system, a plurality of serially related switches used to establish a connection, the first of said switches being accessible over two paths, one of said paths including two line conductors and a first test conductor, the other of said paths including a multiple of said line conductors and a second test conductor, the second of said switches having two wiper sets over which connections are completed and being accessible over a single path including two line conductors and two test conductors, means for seizing said first switch and for operating it into connective relation with said second switch, means dependent upon the test conductor used in seizing said first switch for determining the test wiper to be used by said first switch in seizing said second switch, and means dependent upon the test wiper used in seizing said second switch for selecting the wiper set over which the connection is to be completed.

8. In an automatic switch, four wipers comprising two line wipers and a normally connected and a normally disconnected test wiper for extending connections to a succeeding switch, four incoming conductors comprising two line conductors and two test conductors, said switch being accessible over one path including said line conductors and one of said test conductors and over another path including said line conductors and the other of said test conductors, means responsive over a particular one of said test conductors for connecting up the normally disconnected test wiper, and means for then controlling said switch to extend a connection to a succeeding switch over said line wipers and the normally disconnected test wiper.

9. In an automatic switch, a plurality of wiper sets over which connections are completed, a four-conductor trunk comprising two line and two test conductors over which said switch is accessible, means in said switch responsive when the switch is seized over a path including said two line conductors and a particular one of said test conductors for selecting one of said wiper sets, said means non-responsive when said switch is seized over a path including said two line conductors and the other one of said test conductors to permit the connection to be completed over the other of said wiper sets.

10. In an automatic switch, two wiper sets over which connections are completed, a four-conductor trunk comprising two line and two test conductors over which said switch is

accessible to other switches, means in said switch for applying a potential to said test conductors when said switch is in its normal position, means included in the circuit of one of said test conductors responsive when said switch is seized over a path including said two line conductors and a particular one of said test conductors for selecting one of said wiper sets, means also responsive when said switch is seized for applying a different potential to said test conductors for maintaining the seizing switch in its operated position, for maintaining the wiper selecting means operated, and for maintaining said switch busy to all other switches having access thereto.

In witness whereof, I hereunto subscribe my name this 8th day of February, 1932.

FREDERICK L. KAHN.
